PACKAGE FOR ADHESIVE BANDAGES AND OTHER ARTICLES

John K. Chambers, Orange, Conn., assignor to The Seamless Rubber Company, New Haven, Conn., a corporation of Connecticut

Filed June 5, 1957, Ser. No. 663,701

1 Claim. (Cl. 206—63.2)

This invention relates to packages or wraps for adhesive bandages and other articles, and more particularly to packages for articles which, when distributed, are in sterile condition, the package or covering being of a character to maintain the sterility of the contents and to permit removal of the article without it being contaminated before being put to use. The package may be used for wrapping adhesive bandages such as used in the home and in hospitals, surgeons' gloves, and other articles which have to be sterile before being applied to a wound or otherwise placed in use.

An object of the invention is to provide a package or wrap in which there is marked simplicity of form and economy of material, there being a notable economy in the use of paper or similar material used for wrapping.

Another object is to facilitate the process of wrapping and enable the article to be quickly and conveniently packaged.

A still further object is to enable the packaged article, such as an adhesive finger bandage, for example, to be more easily removed from the package than has been possible heretofore.

In the accompanying drawings:

Fig. 1 is a perspective view showing a package for an adhesive bandage embodying the invention;

Fig. 2 is a perspective view showing a step in the process of wrapping;

Fig. 3 is an enlarged section on line 3—3 of Fig. 1;

Fig. 3A is an end view of the article shown in Fig. 1;

Fig. 4 is a fragmentary view of a wrapping strip containing more than one bandage, at an intermediate step in the process of wrapping;

Fig. 5 is a fragmentary view of the wrapping strip in its initial form;

Fig. 6 is an enlarged section on line 6—6 of Fig. 1;

Fig. 7 is a perspective view showing a modified form;

Fig. 7A is an end view of the package of Fig. 7;

Fig. 8 is a view similar to Fig. 7, showing the wrap in the process of being opened;

Fig. 9 is a view similar to Fig. 8, showing a later stage in the opening of the wrap; and

Fig. 10 is a perspective view showing another method of opening.

In the drawings, the packages selected for illustration are those for an adhesive bandage such as applied to finger cuts and the like, the bandage having a textile compress or pad to be applied to the wound, the compress being intermediate of the ends of a backing exposing an adhesive at opposite sides of the compress. In this form the package is an elongated one, the length being several times the width and the thickness or depth in this case being very slight on account of the waferlike character of the enclosed article. In the case of wrappings for other articles, the relative dimensions may, of course, be different, although in most cases the packaged article will be of elongated or striplike shape.

In the form shown in Figs. 1 to 6, the wrapping for the adhesive bandage is one constructed of a single sheet

2

or blank of thin semi-opaque flexible paper, the blank initially being a flat elongated one having a width such that the same may be folded over the bandage from opposite sides, and the side portions of the blank brought together and adhered to each other substantially at the center of the bandage (longitudinally) and folded downwardly to form a flat narrow two-ply seal 20 extending lengthwise of the package, as shown in Fig. 1. This creates a two-ply joint extending from a line approximately at the center of the package toward one margin of the package. This joint has extremities or edges which in this case terminate at a location such that the face of the package body at which the joint is disposed is left free and unencumbered adjacent the left hand margin, as shown in Fig. 3A, the free or distal extremities of the plies of the sealing fold being in rather close proximity to the longitudinal center line of the package. The fold takes up only a fraction of the package width, preferably being of less than half of such width.

20 The paper blank or strip 21 in its initial flat form is shown in Fig. 5, the same having at one face a coating of adhesive extended over the entire face. This blank or strip may be initially a continuous blank cut to length after the bandage has been wrapped therein, as herein-after described.

25 As shown in Fig. 1, the package length exceeds the length of the bandage 22 to such extent that end portions 22A of the wrapping extend beyond the bandage. The blank 21 is laid on a table or suitable support with the adhesive surface uppermost and the bandage placed on the blank substantially at the longitudinal center of the latter, as indicated in Fig. 5. The bandage illustrated is of a well-known type having a backing strip of suitable material coated with an adhesive mass at one face, the pad or compress being carried at the center of the strip (lengthwise) and the pad being covered by protective facing strips fixed to the backing strip by the adhesive, the facing strips having terminal portions covering the pad or compress and overlapping each other. In the particular embodiment shown, the bandage is laid upon the blank 21 with the backing strip of the bandage uppermost. The side portions of the blank are then folded upwardly over the bandage, and the terminal portions brought together in the relationship shown in Fig. 2.

30 At this stage the terminal portions of the blank extend upwardly from the blank and they are adhered to each other by bringing their coated faces into contact and pressing them together. If desired, the pressing for forming a longitudinal upstanding sealing rib or flange may be effected through the use of pressure rollers, as indicated by the broken lines in Fig. 2. Not only is the lengthwise joint or seam formed, but end seals are created by pressing together the opposing paper faces that are extended beyond the ends of the bandage. The next step is to flatten down the upstanding flange shown in Fig. 2

35 so as to create the structure shown in Fig. 1 wherein the flange lies flat against the package face. The joint part may, if desired, be pressed down and flattened against the package face by a suitable mechanical means or tool.

40 In this form the adhesive applied to one face of the blank is of cohesive nature so that, when the adhesive-coated surfaces at the longitudinal joint portion of the wrap and at the ends of the wrap are pressed into contact with each other, an effective seal against contamination will be provided. It will also be understood that the coating used on the wrap, where such coating comes into contact with the bandage, will not adhere to the bandage and will not in any way interfere with the removal of the bandage from the wrapping. In the drawing, the cohesive adhesive is indicated at 23. Fig. 3 shows the disposition of the coating of adhesive in a region of the wrapped bandage near one extremity of the bandage, and Fig. 6 shows the disposition of the layer

of adhesive in relation to the pad or compress part of the bandage.

When it is desired to use the bandage, the wrapping may be opened conveniently and the bandage taken out and applied without contaminating the pad which is to be applied to the wound. Different modes of opening can be employed but preferably opening will be effected by tearing the seam portion or flange 20, as hereinafter more particularly described in connection with the second form herein disclosed.

In the second form (Figs. 7 to 10) the character of the wrapping material is somewhat different, such material being a polished substantially transparent one such as glassine paper. Also, the structure of the wrapping is slightly different from that in the first form. The width of the strip or blank has substantially the same relationship to the bandage width as in the first form, and as before the side portions of the blank are drawn up and folded over the bandage in a manner such that upstanding opposed narrow flanges are created to produce a sealing joint or seam. In the case under discussion, however, the wrapping paper is so placed laterally relatively to the bandage that the base of the flange or rib structure is slightly to one side of the center line of the package, the result being that in this case the free edge of the flange is in aligned relationship or at any rate in close proximity to the adjacent margin of the wrapper body. In this case the offcenter base line of the joint is indicated at 24, and the free (unfastened) edge of the flange is indicated at 25.

One method of opening the wrapping conveniently and quickly is shown by way of example in Figs. 8 and 9. The package being held between the thumb and index finger of the left hand, the manipulator grasps between the thumb and index finger of his right hand the remote end of the joint flange, as shown in Fig. 8, and pulls the extremity or tip of the flange toward him so as to tear off the flange or remove it at least to a considerable extent, as shown in Fig. 9. In this way the package is broken open lengthwise sufficiently to enable the bandage to be grasped and easily removed.

Another method of opening is to grasp the flange about midway of its length so as to break into the wrap at the middle part, as indicated in Fig. 10. These examples show the facility with which the wrap can be opened, but other methods may be used.

In the form of Figs. 7 to 10, the paper or other wrapping material is adapted to be sealed by heat rather than by pressure alone. The paper used for wrapping, whether glassine or another kind of paper or fibrous material, carries a suitable sealing material of a thermoplastic nature. The thermoplastic substance used, such, for example, as vinyl resin or polyethylene resin, may be contained in the pulp which is to be used in the manufacture of the paper, or it may be applied to the surface of the paper or other material as a separate operation before the strip of paper is made into a package. In the article shown in the drawings, the paper is of the latter kind, the inner surface having throughout a thin coating 26 not adhesive at room temperature but becoming adhesive on application of heat.

In this heat-sealed wrapping, the heat will be applied to the part of the wrapping which will serve as the tearing flange, and also to the two extremities of the wrapping so as to seal the package at the ends, the front and back of the body of the package being in face-to-face contact at the ends throughout the width of the package. These two operations of sealing by heat can be done very conveniently in a wrapping machine. Where the wrapping is done by machine, the wrapper blank will be a continuous strip initially in roll form, and spaced apart bandages can be placed on and folded within this strip. After wrapping (including heat sealing) the strip can be cut transversely, as diagrammatically shown in Fig. 4, to separate the packages. At each end of the wrap the

extension of the latter beyond the extremity of the bandage should be sufficient to provide for an effective end seal.

One advantage of the wrap herein described is marked economy in the use of the paper or like material. In wrapping, only one strip of paper need be used, and only one roll of paper need be handled. By wrapping by this method in a wrapping machine, the latter can have high efficiency, thus decreasing the cost of the product. Moreover, the package has considerably enhanced facility of opening, which is an important advantage.

It is understood that the paper is sufficiently porous to permit sterilization of the packaged article such as a bandage, plaster, glove or the like, and that after sterilization the package, in normal handling and storage, cannot be penetrated by bacteria; and it will also be understood that the package can be opened for extraction of the article in a manner such that in handling it contamination can be inhibited.

In the package herein described, the wrapper is formed to provide a body extended continuously across the bottom of the package and extended across the upper part of the package to terminals formed as longitudinal facing flanges brought together and sealed to each other and flattened down to lie flatwise against the package body at the upper face of the latter. The facing flanges form a two-ply tearing flange of substantially less width than the package and located asymmetrically with respect to the upper face of the package. In the forms shown, the tearing flange has a width approximating one quarter of the width of the wrapper body. The flange extends throughout the length of the wrapper, and the sealed-together ends of the wrapper lie substantially in the plane of the wrapper body.

It is noted also that the package containing the article has minimum thickness or depth, the same not being encumbered by plies or otherwise in a manner to create a thick or clumsy package. Two plies of the paper are used in creating a seam and these are of thin flexible material, and, moreover, are of limited lateral extent so that what slight protuberance from the package body is present is localized and of minimum area.

The forms herein disclosed are by way of example only, and various other forms embodying the invention may be used without departure from the claim.

What I claim is:

A packaged adhesive bandage comprising a rectangular strip-like wrapper of flexible, foldable, tearable material of greater length than the adhesive bandage, said wrapper having four parallel fold lines extending longitudinally of the strip-like wrapper from one end to the other, dividing the wrapper into five panels, said five panels including a middle panel, a pair of panels adjacent and folded back to overlie the middle panel and a pair of outermost panels, the two innermost fold lines being equally spaced from opposite longitudinal edges of the wrapper and the two outermost fold lines being equally spaced from opposite longitudinal edges of the wrapper, the middle panel being at least as wide as the adhesive bandage and the sum of the widths of the panels adjoining the middle panel being equal to the width of the middle panel, the width of the outer panels each being no greater than half the width of the middle panel, the adhesive bandage being interposed between the inner surfaces of the middle panel and the folded back panels adjoining the middle panel, the opposing faces of the middle panel and panels adjoining the middle panel being sealed together transversely beyond the ends of the adhesive bandage, the outermost panels being in faced contacting relation and sealed together throughout said contacting faces to form a longitudinal flange which can be pivoted from a position substantially perpendicular to the package to give the package a T-shaped configuration when viewed from one end to a position overlying one of the panels adjoining the middle panel to

give the package a relatively flat appearance when viewed from one end.
